CLAIM

The ornamental design for a curved bookshelf, as shown and described.

DESCRIPTION

FIG. 1 is a front perspective view of a curved bookshelf showing the new design;

FIG. 2 is a rear perspective view thereof;

FIG. 3 is a rear exploded view thereof showing the multiple pieces of the middle portion of the curved bookshelf;

FIG. 4 is a front view thereof;

FIG. 5 is a back view thereof;

FIG. 6 is a left side view thereof;

FIG. 7 is a right side view thereof;

FIG. 8 is a top view thereof; and,

FIG. 9 is a bottom view thereof.

The portions shown in broken lines are not part of the claimed design.

1 Claim, 7 Drawing Sheets(56)
